(57) **CLAIM**

The ornamental design for a clear ice maker, as shown and described.

DESCRIPTION

FIG. 1 is a top-facing perspective view of the clear ice maker showing my new design;

FIG. 2 is a top plan view thereof;

FIG. 3 is a bottom plan view thereof;

FIG. 4 is a right-side elevational view thereof, the left-side elevational view being identical thereto; and,

FIG. 5 is a front elevational view thereof; the rear elevational view being identical thereto.

The broken lines in the drawings depict portions of the clear ice maker that form no part of the claimed design.

1 Claim, 5 Drawing Sheets
